UNITED STATES PATENT OFFICE.

FRANK BUCHANAN, OF SYRACUSE, NEW YORK.

INCANDESCENT-ELECTRIC-LAMP FIXTURE.

1,162,974.

Specification of Letters Patent.

Patented Dec. 7, 1915.

Application filed August 25, 1913. Serial No. 780,424.

To all whom it may concern:

Be it known that I, FRANK BUCHANAN, a citizen of the United States, and a resident of Syracuse, in the county of Onondaga and State of New York, have invented a new and useful Incandescent-Electric-Lamp Fixture, of which the following is a specification.

This invention has for its object an incandescent electrical lamp fixture and particularly the arrangement of the reflector casing and the support for the lamp, and it consists in the novel combinations and constructions hereinafter set forth and claimed.

In describing this invention reference is had to the accompanying drawings in which like characters designate corresponding parts in all the views.

Figure 1 is a vertical sectional view, partly in elevation, of this fixture, the lamp being shown therein and the position of the small lamp, when a socket extension is used, being indicated in dotted lines. Fig. 2 is a section on line A—A Fig. 1. Fig. 3 is an enlarged fragmentary view illustrating the manner of attaching the socket support in position.

This lamp comprises generally a bell shape casing having an upwardly or outwardly extending axial shank and a lamp socket carried within the shank. As this lamp fixture is designed for use where there are smoke and vapors, as in round houses, it is provided with a hinged door having a glass window.

1 is the bell shape casing having an upwardly extending axial hollow shank 2, the shank being provided with an axial threaded nipple 3 for connection to the conduit enclosing the service wires. The nipple 3 is of less diameter than the shank and the shank is slightly tapered upwardly. The inner side of the bell of the casing 1 is provided with a polished or enameled reflecting surface. 4 is the glass door which protects the reflector and the lamp from smoke and vapor.

5 is the lamp socket in the shank 2, and 6 is the socket support, the latter extending across the passage of the nipple 3 in order that the service wires may lead directly to the terminals of the socket 5, and being secured to the inner end wall of the shank by fastening members located on opposite sides

of the nipple. The fastening members are screws 7 threading through bushings 8 which in turn thread into the end wall of the shank from the outer side thereof, the bushings extending below the inner face of said end wall so that the socket support 6 bears against the bushings and not against the inner face of the end wall of the shank. This feature is particularly desirable as the casing is usually enameled or otherwise coated and the enamel accumulates somewhat within the shank so that an uneven surface is usually present against which the socket support would seat if the bushings were not used.

9 designates the large lamp which plugs into the socket 5 and 10 designates the small lamp which plugs into the extension socket similar in shape to the body 11 of the larger lamp, but having a socket for the smaller lamp.

What I claim is:

1. The combination of an incandescent electric lamp fixture and an incandescent electric lamp, the fixture comprising a bell-shaped casing having an upwardly extending hollow shank arranged coaxially with the axis of said casing, a lamp socket carried within the shank and arranged to support the lamp in a position extending substantially axially of the casing, the bell portion of the casing extending beyond the free end of the lamp and a closure for the open end of the bell, substantially as and for the purpose described.

2. An incandescent electric lamp fixture comprising a bell shaped casing, an upwardly extending axial hollow shank, the shank being provided with an axial nipple for connection with the conduit, a lamp socket within the shank, a support for the socket opposed to the inner end wall of the shank, the support extending on opposite sides of the passage of the nipple, and fastening members extending through the end wall on opposite sides of the nipple, substantially as and for the purpose set forth.

3. An incandescent lamp fixture comprising a casing, a lamp socket within the casing, a support for the socket opposed to the wall of the casing, bushings extending through said wall and engaging at their inner ends with the support, and screws ex-

tending through the bushings and threading into a support, the bushings serving to hold the support away from said wall, substantially as and for the purpose set forth.

5 In testimony whereof, I have hereunto signed my name in the presence of two attesting witnesses, at Syracuse, in the county

of Onondaga, in the State of New York, this 15th day of August, 1913.

FRANK BUCHANAN.
